METHOD AND APPARATUS FOR SORTING
AND SETTING DOUBLE-HEADED CHAP-
LETSWilliam H. Watt, McKeesport, Pa., assignor to
Columbia Radiator Company, a corporation of
Pennsylvania

Application October 13, 1937, Serial No. 168,708

7 Claims. (Cl. 22—9)

My present invention relates to the manufacture of cast iron radiators such as those of the steam and hot water types intended for domestic use, and more particularly concerns a method and apparatus for sorting and setting double-headed chaplets which I utilize in connection with such radiator manufacture. As the term is herein used, a double-headed chaplet consists of a slender stem or shank at each extremity of which a disk-like head is disposed.

In manufacturing radiators of the above types in accordance with prior practice, wire chaplets are used extensively at certain stages in the manufacturing procedure but have been applied to the appropriate mold pattern or core by hand. This has not only resulted in retarding the entire procedure of making and assembling radiator molds and cores but has had the additional disadvantage of tying up workmen on a simple but tedious type of work wherein the necessary requirements of speed and accuracy are not fulfilled, especially when production of completed radiator molds ready for pouring is on a continuous production basis. If chaplet setting could be accomplished automatically or mechanically, these men could be released for more important work. Insofar as I am aware, it has been the invariable custom to set chaplets by hand and to the best of my knowledge and belief no satisfactory procedure or apparatus has been developed or devised to eliminate these manual operations. The use of double-headed chaplets has not even been attempted in prior practice.

It is, accordingly, one of the objects of my present invention to produce both a procedure and an apparatus whereby chaplets can be simply, quickly and accurately set mechanically or automatically at those stages in the manufacture of radiators where chaplet setting is required.

Another object of my invention resides in obviating the difficulties and disadvantages inherent in the prior practice of setting chaplets and in introducing new procedure and new apparatus which have further advantages peculiar to themselves.

A further object of my invention resides in utilizing a double-headed chaplet and in providing procedure and equipment for sorting and setting the same on the molds, flasks, cores or other parts used in casting radiator shells or sections while at the same time eliminating hand or manual setting of chaplets as hitherto practiced.

A still further object of my invention resides

in the provision of a chaplet sorting box wherein double-headed chaplets are prepared for setting by aligning them in a series of tubes.

A still further object of my invention resides in a setting double-headed jig provided with magazine tubes for setting chaplets and to which magazine tubes the chaplets are transferred after their preparation in the sorting box.

Other and further objects and advantages reside in the detailed procedural and structural features hereinafter described and claimed and in such other features as will be understood from or pointed out in the subsequent description.

In the accompanying drawings wherein like numerals designate corresponding parts throughout the various views:

Figure 1 is a plan view of a chaplet sorting box in accordance with my present invention;

Fig. 2 is a side elevational view, with parts broken away, of the sorting box of Fig. 1;

Fig. 3 is a side elevational view of the setting jig of my present invention in operative association with a flask or mold and showing connection to an air hoist;

Fig. 4 is an end elevation of Fig. 3;

Fig. 5 is a plan view of certain parts of the setting jig with portions broken away and in section;

Fig. 6 is a side elevational view of the setting jig on an enlarged scale;

Fig. 7 is a plan view of a drag flask utilized in connection with the present invention;

Fig. 8 is a view partly in elevation and partly in section taken on line VIII—VIII of Figs. 7 and 9;

Fig. 9 is a transverse section through the drag flask of Fig. 7 taken on line IX—IX of that figure;

Fig. 10 is a transverse section through a complete assembly ready for pouring or casting of a radiator section;

Fig. 11 is a fragmentary longitudinal section taken on line XI—XI of Fig. 10;

Fig. 12 is a plan view of a typical sand core utilized in connection with the present invention;

Fig. 13 is a perspective view of a chaplet of the kind herein utilized; and

Fig. 14 diagrammatically indicates the stages of the chaplet setting operation.

Referring first to Figs. 1 and 2 which illustrate a sorting box which is used to prepare double-headed chaplets for the setting jig shown in Figs. 3 to 6, the numeral 10 indicates a hexagonal wooden box or container of sufficient internal

capacity to receive a considerable number of the metal tubes 11. These tubes 11 are shorter in height than the box 10 (see Fig. 2) and since they rest upon the bottom of the box a space or chamber 12 is formed between the tops of the tubes and the top of the box. This hexagonal box is preferably made up of a number of trapezoidal sections which are suitably held together in assembled position by metal straps 13 which pass around the box at vertically spaced points as shown. These straps are provided with hinges 14 having removable pintles 14' so that the box can be opened when tubes are to be removed and may be formed in two pieces, one of which 15 is removable as is clearly apparent in Fig. 1. The other piece 16 is formed with ears or lugs 17 from which threaded bolts or the like 18 extend and the piece 15 is provided with apertures through its terminal portions through which said bolts are adapted to pass. The parts are normally held together by the nuts 19. The strap construction may, however, be varied and may open in any suitable way to permit opening of box 10.

Inasmuch as my present invention involves the aligning of series or sets of double-headed chaplets of the type shown in Figure 13 in the tubes 11 in the sorting box 10, I provided such box with shaking or agitating means. Such may be in the form of handles (not shown) affixed to the box or the straps at any suitable location and by means of which the box 10 may be manually agitated, but for production purposes I preferably provide for mechanical shaking. This can readily be done by providing one of the metal straps 13 with the oppositely extending metal ribs 20 on the outer end of each of which is a suitable metal plate or bracket 21 to which a reciprocating or shaking part of an associated agitating device can be readily attached. As shown, the ribs 20 are attached to one strap 13 by welds 22 and the brackets 21 are also attached to said ribs 20 by the welds designated at 23. The sorting box has a bottom plate 24 of hexagonal shape provided with upwardly extending spaced reinforcing lugs 25 and, if desired or preferred, the sorting box may be provided with a carrying handle at its top, as designated by the numeral 26, suitably secured to box 10 by plates or the like 27.

In utilizing and operating the sorting box just described, the tubes 11 are positioned therein and a large number of chaplets is deposited in the space 12, the tubes 11 being of such diameter that the chaplets can pass therewith in an endwise direction only and not transversely. Then by manually or mechanically shaking or agitating the sorting box with the chaplets deposited as described, these chaplets gradually and successively fall into the tubes, and this action is continued until all the tubes are filled with chaplets. Each tubeful of chaplets will hereinafter be referred to as "an aligned set of chaplets." As will be understood, the tubes are tightly held in place in the box by the strap structures referred to. When the tubes 11 are full of aligned sets of chaplets, excess chaplets, if any, are removed and then the sorting box is opened and the tubes individually removed and the aligned sets of chaplets transferred to the setting jig 28 now to be described. The chaplets are transferred from the sorting box tubes to the setting jig tubes by hand or in any suitable manner. For example, a sorting box tube full of chaplets is placed in socket 49 of magazine tube 36 and the chaplets

caused to drop into the latter tube without loss of alignment. Tubes 11 and 36 are of approximately the same diameter and length.

The construction of the setting jig 28 will be clear from Figures 3 to 6, inclusive, and, as shown in these figures, the jig comprises a lower or stationary plate 29, which may be made of aluminum or other suitable metal, a sliding plate 30 on the plate 29, a top plate 31 spaced above plates 29 and 30, and a series of metal rods 32, four being shown in Fig. 5, by means of which the lower plate 29 and the upper plate 31 are held as a unit in predetermined spaced relationship. The metal rods 32 pass through and are suitably secured at one end to top plate 31 by means of the washer 15 and nut assemblies 33 and the rods 32 at their other ends are suitably secured in or to the lower or stationary plate 29, the sliding plate 30 being arcuately cut out as designated at 34 in order that the sliding plate may perform its sliding functions without interference from said rods.

The sliding plate 30 is provided with a plurality of transverse series of apertures or openings designated at 35, twenty being shown in Figure 5, although this number may vary from 12 to 24, there being four such transverse series and from three to six openings in each series. Magazine tubes 36 pass through these apertures or openings 35 which, however, are of sufficient extent to permit linear movement of the sliding plate 30 on stationary plate 29 in response to movement of handle or lever 37 which is intermediately connected to the stationary plate 29 by means of a retractive spring 38 and which is eccentrically connected at its inner end to a cam or the like 39 mounted on a vertical stub shaft 40 which passes into the lower or stationary plate 29. The sliding plate 30 is provided with a hole 41 having countersunk wear or contact members 42 on either side secured by screws or the like 43 and which are acted upon by cam 39 so that when the handle or lever 37 is moved to the left (clockwise) in Figure 5, sliding plate 30 is also caused to move to the left and such movement is limited either by the cam contour or by the righthand extremity of apertures or openings 35 contacting the magazine tubes 36.

The siding plate 30 is provided with a plurality of latch supports or the like 44 which pass through and are fixed to said sliding plate 30 and which project through said stationary plate 29, slots 45 being provided in the latter plate to permit movement of said supports 44 when sliding operation of said sliding plate is effected. Each support 44 is provided at or near its lower end with a latch element 46 in the form of a small, thin plate or disc which normally projects into a slot 47 in the lower end of each magazine tube 36 a distance sufficient to retain the chaplets within such tubes until such time as it is desired to discharge or deposit chaplets therefrom. It will be noted from Figures 5 and 6 in particular that one such support and latch is provided for each magazine tube and hence the number of latching elements is equal to the number of magazine tubes and is also equal to the number of openings in sliding plate 30.

As shown in Figure 6 particularly, the magazine tubes 36 pass through upper plate 31, the apertures 35 in sliding plate 30 and the lower stationary plate 29 and each tube is preferably provided with a tapered frusto-conical lower end 48. These magazine tubes 36 are also preferably provided at their upper ends with the short tubes or

5   sockets 49 which are suitably secured to the tubes 36 as by brazing, welding, threading, etc. and the purpose of which will be hereinafter explained. The stationary lower plate 29 is also provided with the uprights 50 which are secured at their lower ends in the sockets 51 which are secured to said plate as at 52. These uprights, which as shown are in the form of metal tubes, have secured thereto the extensions 53 which cooperate with the upper plate 31 already described in a manner clear from Fig. 6, one such extension engaging the upper surface of plate 31 and the other the under surface thereof.

10   The ends of lower stationary plate 29 are provided, on their under side, with the downwardly projecting centrally disposed pointed elements 54 which serve for registering the setting jig as will hereinafter be explained.

15   The uprights 50 of the jig are preferably connected as shown in Figure 3 to an air hoist or other lifting means designated as a whole by the numeral 55 to provide for raising and lowering the jig as required. The details of the lifting means form no part of the present invention and 20   are of conventional design.

25   It will thus be clear from the foregoing that each actuation of lever or handle 37 (to the left in Fig. 5) will cause sliding plate 30 to move (to the left) with respect to stationary lower plate 29 and as sliding plate 30 so moves it carries with it the latch supports 44 causing each latch element 46 to move out of a slot 47 in magazine tubes 36, thus enabling a chaplet to be deposited from each such magazine tube on a flask, core or 30   other mold part used in connection with the manufacture of radiators as will hereinafter be more fully understood. When handle 37 is released the spring 38 immediately retracts it and hence again latches the magazine tubes and this happens immediately after a chaplet is discharged from each magazine tube and prevents additional chaplets from being discharged. These operations will be especially clear from Fig. 14. The taper at the lower end of the magazine tubes provides the maximum clearance between the outer walls of 35   tube and adjacent mold or core surfaces to prevent disturbing of sand when tubes are lowered into position for setting chaplets. Moreover, accurate positioning of the chaplets is of importance because the dry sand core must be held firmly in exact position between the drag and cope molds to maintain the desired mold cavity until filled with molten metal, thereby securing the desired thickness of metal walls in the casting.

40   It will be noted from Figures 3 to 6, inclusive, that the ends of lower stationary plate 29 of the setting jig are provided at each end with lugs or flanges 56 secured to brackets or the like 57 at their upper ends by means of nut and bolt assemblies indicated by the numeral 58. The lower ends of these lugs or flanges 56 are each connected below stationary plate 29 by a connecting bar 59 provided with a central hole 60 for the passage therethrough of pointed members 54 45   and serve as spacers when the jig is used to deposit chaplets upon a sand core positioned upon a set of chaplets previously deposited on a drag flask, as will be understood hereinafter.

50   Referring now to Figures 7 to 9, inclusive, the numeral 61 designates a drag flask, i. e., the lower or bottom mold member of the complete assembly unit as it is prepared for pouring or casting operations. The drag flask 61 is made up of the sides 62 which are shown to be concavo-convex but 55   which may have any other shape depending upon

5   the design of radiator to be produced. These sides 62 are connected at spaced intervals by transverse ribs 63 from each of which a plurality of tapered projections 64 rise and these projections are connected with each other and with the flask sides by web-like portions 65. The flask has ends 66 from which extend handle members 67 and each such handle member is provided with a central web 68 apertured at 69 and it is these apertures 69 that are adapted to receive the pointed members 54 of the setting jig and thus to cause registry of the magazine tubes 36 with the projections 64 of the flask in such manner that when the setting jig is actuated as explained to deposit a single chaplet simultaneously from each magazine tube these chaplets are positioned on the projections as indicated at 70 on Figure 7.

10   The cope flask 61', as shown in connection with Fig. 10, is identical with the drag flask 61 of Figs. 7 to 9 except that the cope flask is the reverse of the drag flask as will clearly be understood from Figure 10 and to indicate similarity of parts the same numerals have been used but with a prime mark ('') thereafter. In Figure 10 the flask-core assembly is shown as ready for the pouring operation and from this figure it will be apparent that the drag flask 61 is on the bottom, that a set of chaplets 70 is upon the projections 64, that a sand core 71 rests upon the chaplets, that a second set of chaplets 70 rests upon the sand core 71 and that projections 64' of cope flask 61' rest upon the second set of chaplets.

15   This sand core 71 is shown more in detail in Figure 12 and generally consists of a series of bars or core members 72 made of sand and connected at each end by transverse bars 73 which are usually provided with handle-like extensions 74 provided with frusto-conical projections 75 centrally disposed above and below said members. This sand core is made in any conventional manner and is ordinarily made from sand which has been treated with oils, formed into shape and baked until it has a certain hardness and rigidity which makes it suitable for use in connection with casting operations. There may, of course, be any suitable number of bars 72, e. g. 3-6. As shown in Figure 11, the handle-like portions 74 lie between the handles 67, 67' of the drag and cope flasks, respectively, and the frusto-conical projections 75 extend partway into the openings 69, 69' in the webs 68, 68 and serve to effect registration and spacing of the two flask members and the intermediate core.

20   The chaplet 70 which has been heretofore discussed is shown in Figure 13 and consists of top and bottom disc-like portions 76 centrally connected in parallel relationship by a stem or shank 77. So far as I am aware this particular form of chaplet has never been used before in connection with the manufacture of radiator sections in accordance with this invention nor has there been available any satisfactory mechanical or automatic equipment for setting chaplets of any type in place in radiator manufacture, but on the contrary, such operations have been heretofore carried out by hand as above explained.

25   In manufacturing radiator sections in accordance with the present invention, a drag flask is filled with sand of the usual type, e. g., black molding sand, used in such operations under 30   the usual conditions, i. e., the sand is compacted by a jolt squeeze machine of usual type. The setting jig, the magazine tubes of which have been previously charged with chaplets in accordance with the foregoing description, is now 35   75

placed in registry with the drag flask and a set of chaplets deposited thereon and then the setting jig removed by the air hoist or otherwise. A sand core of suitable character is then placed 5 upon the deposited chaplets and in proper association with the sand-filled drag flask and a second set of chaplets deposited on the sand core by means of the setting jig which is thereafter again removed. The cope flask is placed upon 10 the chaplets resting upon the sand core to produce the flask-core assembly, such as is illustrated in Figure 10, and then this flask, mold, core and chaplet assembly is conveyed to the pouring or casting department where molten 15 metal is poured or cast into the assembly and, as will be appreciated from Figure 10 and from what has been hereinabove described, this metal hardens around the chaplets and assumes a form determined by the shapes of the various mold parts. The molten metal freezes or solidifies 20 around the chaplets and thus the chaplets are incorporated in the ultimate radiator section. Hence the importance of the accurate setting of the chaplets as well as requisite speed and accuracy in making up the flask-core assemblies 25 so as not to retard the procedure of casting radiator sections as a whole. After the sections have hardened and cooled to the desired extent the flasks and core are removed and a number 30 of sections assembled into a radiator of desired size, these operations being conventional and well known in the industry and do not per se form a part of my present invention. Conventional surface finishing operations may be carried out on the sections and/or on the completed 35 radiators.

The foregoing is intended as illustrative rather than limitative and within the principles and scope thereof various modifications, alterations, 40 substitutions and additions can be made within the terms of the appended claims. These are all deemed a part of the present invention and will be clearly understood by those skilled in this art.

Having thus described my invention, what I 45 claim as new and desire to secure by Letters Patent is:

1. A method of setting double-headed chaplets in predetermined spaced relationship on a flask or core which comprises the steps of producing a plurality of vertically aligned sets of such 50 chaplets arranged in columnar form, transferring a number of such sets of chaplets to magazine tubes of a setting jig, feeding a single chaplet simultaneously from each such magazine tube and precisely positioning each such chaplet at 55 a predetermined point on the flask or core.

2. In a method of making a radiator wherein a radiator section is cast in a flask-core assembly the steps which comprise producing a plurality of aligned sets of double-headed chaplets, transferring a number of such aligned chaplet sets to setting jig magazine tubes, positioning such magazine tubes over and in proper relationship to a drag flask, simultaneously discharging a single chaplet from each magazine tube onto said flask, removing said setting jig, positioning a sand core on said chaplets, repositioning the setting jig and repeating the chaplet discharging operation on said core.

3. In a method of making radiators wherein a

radiator section is cast in a flask-core assembly the steps which comprise assembling a series of chaplet-receiving tubes, randomly charging a plurality of double-headed chaplets on top of said tubes, causing said chaplets to fill said tubes in vertically aligned relationship to form sets of chaplets arranged in columnar form, transferring a number of such sets to the magazine tubes of an associated chaplet setting jig, positioning said magazine tubes over and in predetermined relationship to certain of said assembly elements and discharging a single chaplet simultaneously from each magazine tube onto said assembly elements.

4. A jig for setting double-headed chaplets on a flask or core in the manufacture of radiators comprising a stationary lower plate, a slidable plate upon said stationary plate, an upper plate vertically spaced from said stationary and sliding plates, means to maintain said plates in predetermined relationship, magazine tubes extending through all of said plates, latch mechanisms on said slidable plate normally obstructing said magazine tubes, said sliding plate being adapted to be moved along the surface of said stationary lower plate and to cause said latch mechanisms to move out of tube-obstructing position and means to slide said slidable plate.

5. A jig for setting double-headed chaplets on a flask or core in the manufacture of radiators comprising spaced upper and lower plates, a slidable plate on said lower plate and adapted to move back and forth upon the surface thereof, means for effecting back and forth sliding movement of said slidable plate, magazine tubes extending through all such plates, and latching mechanisms mounted on said sliding plate, adapted to move therewith and having obstructing and non-obstructing positions with respect to said magazine tubes.

6. Apparatus for setting double-headed chaplets in the manufacture of radiators which comprises means for discharging a single chaplet simultaneously from the bottom of each of a plurality of vertically aligned sets of such chaplets, said means including a plurality of magazine tubes held in spaced relationship and a corresponding number of latch mechanisms normally obstructing the bottoms of said magazine tubes and adapted to be retracted simultaneously to a non-obstructing position.

7. Apparatus for setting double-headed chaplets in the manufacture of radiators which comprises means for discharging a single chaplet simultaneously from the bottom of each of a plurality of vertically aligned sets of such chaplets, said means including a plurality of plates one of which is relatively slidable, a plurality of spaced magazine tubes passing through said plates, said magazine tubes being each provided with a transverse slot extending partially therethrough near the bottom thereof, a number of latch mechanisms provided on said slidable plate equal to the number of magazine tubes and normally projecting into said magazine tube slots, said latch mechanisms being retractable out of said slots when sliding movement is imparted to said slidable plate and means to effect such sliding movement of said slidable plate.

WILLIAM H. WATT. 70
